UNITED STATES PATENT OFFICE.

JOHN SUTTON, OF ISLIP, NEW YORK.

FILTER.

SPECIFICATION forming part of Letters Patent No. 470,355, dated March 8, 1892.

Application filed March 10, 1891. Serial No. 384,432. (No model.)

To all whom it may concern:

Be it known that I, JOHN SUTTON, of Islip, in the county of Suffolk and State of New York, have invented a new and useful Improvement in Filtering Apparatus, of which the following is a specification.

My invention relates to an improvement in filtering apparatus in which provision is made for obtaining a great extent of inlet and outlet filtering-surface within a comparatively small space and for manipulating the filtering material in such a manner as to increase or diminish the size of the pores throughout the filtering material at pleasure and for packing and operating the filter in a convenient and expeditious manner.

A practical embodiment of my invention is represented in the accompanying drawings, in which—

20 Figure 1 is a view of the apparatus in side elevation. Fig. 2 is a view in end elevation. Fig. 3 is a view in side elevation, partly in section, showing the filter turned in position for packing the upper compartment. Fig. 4 is a vertical transverse section through line $x-x$ of Fig. 1; and Figs. 5 and 6 are views in detail representing, respectively, the spindle in longitudinal section and end elevation.

The particular class of filter which I have 30 selected for the purpose of illustrating my invention is that in which the filtering-vessel is supported by means of trunnions in a suitable frame, so as to be swung from a horizontal position to a position with its removable 35 or opening end upward—such, for example, as shown in Letters Patent No. 406,603, granted to me July 9, 1889. I do not, however, limit myself to filters of that class only, as it will be obvious that many, if not all, of the features of my present invention are applicable 40 to filtering-vessels of other well-known forms and not adapted to be swung into different positions. I have also shown the supporting-frame as mounted on a truck for convenience 45 in transporting the apparatus.

A represents the truck, to the opposite sides of which the standards a are fixed, the latter being provided at their upper portions with suitable bearings a' for the reception of the 50 trunnions of the filtering-vessel. The filtering-vessel is here shown of cylindrical form and comprises two distinct compartments B

and B' , separated from each other by an immovable partition b , impervious to liquid. The partition b forms the common floor of the 55 two compartments and has flanges b' , extending in opposite directions from its periphery, within which the adjacent ends of the casings which form the walls of the compartments B and B' are received and to which they are secured liquid tight. The opposite ends of the casings of the compartments B and B' are provided with reinforcing-rims b^2 , fixed snugly thereto and adapted to receive the covers C and C' , so as to form a liquid-tight joint. The covers 60 C and C' are hinged to the edges of the ends, sufficient play being provided for at their hinged connections to admit of the movement of the cover bodily toward its seat, and suitable screws c are adapted to engage the cover 65 and threaded seats or lugs in the rim for drawing the cover into snug contact with its seat.

The general structure of the filtering-vessel and its covers as thus far described is 70 quite similar to that shown and described in my patent above referred to, and, as mentioned therein, the vessel might be cast with its floor and walls integral, the form shown being the one preferred in practice. The rim 75 of the common partition or floor b has the trunnions b^3 fixed thereto or formed integral therewith upon diametrically-opposite sides, and in proximity to the trunnion upon the inlet side is provided with conduits b^4 and b^5 , 80 formed integral with the rim and leading in opposite directions from the common inlet-channel b^6 in the trunnion and communicating the one with the compartment upon one side of the floor b and the other with the compartment upon the opposite side of the floor b .

The common inlet-channel is provided with a stop-cock b^7 for the purpose of shutting off the liquid to be filtered from both of the compartments B and B' , and each of the conduits 95 b^4 and b^5 is provided with its own independent cock b^8 and b^9 for the purpose of letting on and cutting off the flow of the liquid to be filtered from either one of the compartments independently of the other. The barrels of the cocks b^8 and b^9 may be cast integral with the rim of b . There is also provided in connection with the conduits b^4 and b^5 connections b^{10} and b^{11} for the purpose of admitting

water to the compartments for flushing or other purposes. The connections b^{10} and b^{11} are provided with suitable stop-cocks b^{12} and b^{13} , and they are preferably so arranged with respect to the cocks b^8 and b^9 that the latter (which may be ordinary three-way cocks) may be utilized to simultaneously shut off communication between the channels b^4 and b^5 and the compartments B and B' and open communication between the connections b^{10} and b^{11} and said compartments.

The trunnion b^3 upon the outlet side is provided with a channel b^{14} for the discharge of the filtered liquid, which channel communicates at points between the filtering-vessel and its bearings with the chambers for the filtered liquid within the compartments B and B' by means of branch pipes b^{15} b^{16} , each provided with its stop-cock b^{17} b^{18} to shut off the flow from either one of the compartments independently of the other, as may be desired. Outlet-cocks b^{20} and b^{21} communicate with the interiors of the stop-cocks b^{17} b^{18} to send the liquid from either compartment to waste. The branch pipes b^{15} and b^{16} are also each provided with a test-cup D and D', preferably of glass, to which are attached vents, the flow of the gases therethrough being controlled by suitable cocks d d' .

As the structures and arrangements of the filtering devices within the two compartments B and B' and the means for manipulating them are substantially duplicates of each other, the description of one will be sufficient.

The floor plate or frame is of a skeleton formation and comprises a series of ribs e, radiating from a central ring or hub E, and is provided with feet e', located at intervals and here shown as projecting downwardly from the ring or hub E to permit the free flow of the liquid over the partition-floor b beneath and upwardly between the ribs of the plate. It is intended that this floor-plate shall have a diameter substantially equal to that of the compartment in which it is placed and that it shall rest at the inner end of the compartment upon the partition b when in normal position and at the same time have a free sliding movement upwardly or downwardly away from the floor b under the impulse of an operating-spindle, as will be hereinafter more particularly referred to. A hollow spindle F extends from the partition b upwardly to a position to enter a socket c therefor in the cover C when the latter is in closed adjustment, and the lower end of said spindle is provided with feet f, located at intervals around the margin of its lower end to admit of the flow of the liquid from the space in proximity to the partition b into the interior of the spindle. The said spindle is further provided at its lower end with a right-hand screw-thread f' , adapted to engage a corresponding thread within the hub or ring E of the floor-plate. The floor b is preferably provided with a shallow recess b^{19} at the point where the feet of the spindle rests thereon.

About midway of its length, within the compartment B, the spindle F is provided with an annular groove f^2 for the reception of one or more thumb-screws for adjusting a double floor-plate, as will hereinafter appear. The said spindle is reduced in size near its upper end and provided with a shoulder f^3 , upon which a screw-threaded sleeve or collar f^4 is adapted to seat. The screw-threaded collar f^4 is made removable from the spindle F, so that the several plates, which will be hereinafter referred to, may be fitted to slide in close contact with the body of the spindle, instead of leaving the space which would be required were they to slide over the exterior face of the screw-thread upon the collar f^4 . The collar f^4 is held in position upon the spindle and prevented from rotating relative thereto by means of a key f^5 , which extends transversely through the spindle and is engaged with a recess f^6 in the upper edge of the collar. The interior of the hollow spindle F communicates with the space immediately beneath the cover C by means of openings f^7 , extending laterally therethrough. The upper end of the said spindle is provided with a squared socket f^8 , into which the shank g of an operating-lever G (here shown as a hand-wheel) is adapted to fit, the latter extending through a suitable stuffing-box g', fixed to the cover and closing liquid tight the opening c^2 in the cover, through which the shank g extends. A setscrew g², extending through the side of the cap in which the shank g is supported into position to engage the said shank, serves to lock the operating-lever in its position with its end in the squared socket f^8 .

A top plate or frame, quite similar to the bottom plate or frame hereinbefore referred to and comprising a series of ribs h, radiating from a central ring or hub H, is provided with a screw-thread within its hub, adapted to register with the screw-thread upon the collar f^4 , seated upon the spindle, the thread upon the collar f^4 being a left-hand thread, or the opposite of that upon the lower or inner end of the spindle.

Intermediate between the top and bottom plates or frames referred to there is located what I am pleased to term a "double floor-frame," comprising ribs or arms i, recessed to open communication between them and radiating from a central ring or hub I, the latter provided with a bore adapted to embrace, with an easy sliding fit, the spindle F. Thumb-screws i', one or more in number, are seated in threaded perforations in the ring or hub I, and are adapted to project within the same into the annular groove f^2 in the spindle, and thereby prevent the double floor-frame from moving lengthwise of the spindle. The thumb-screws i' are provided with shoulders i², which abut against the hub or ring I before the end of the screw engages the bottom of the groove f^2 , and therefore leave the spindle free to turn independently of the double floor-frame. Perforated plates K K'

are seated upon the opposite faces of the double floor-frame, and corresponding perforated plates $K^2 K^3$ are seated upon the faces of the floor and top frames, the spaces between the plates upon the opposite sides of the double floor-frame and the top and bottom frames, respectively, forming chambers for the reception of filtering material L . There are also interposed between the perforated plates $K K' K^2 K^3$ and the filtering material additional perforated plates $k k'$, &c., the perforations in the latter being smaller than those in the former, as is usual, and such other perforated or porous membrane may be interposed, as is common in the art for filtering purposes. The several perforated plates are provided with central openings adapted to receive the spindle F with a close sliding fit.

In assembling the parts the floor frame or plate is first placed in position upon the partition b . The spindle F is then screwed into its hub E . The perforated plates $k^2 K^2$ are slid down over the spindle into engagement with the floor-frame and the first stratum of filtering material put in place. The perforated plates $k K$ are then slid down over the spindle into engagement with the filtering mass. The double floor-frame is then slid over the spindle and secured in position by the thumb-screws i' , then the perforated plates $K' k'$, then the second stratum of filtering material, then the perforated plates $k^3 K^3$, then the screw-threaded collar f^4 is adjusted upon the spindle and the top frame screwed thereon into engagement with the perforated plate K^3 ; or the collar f^4 might be first screwed into the hub H of the top frame and the collar and top frame then be simultaneously adjusted upon the spindle. The cover C being now closed and secured and the operating-lever adjusted, the spindle F may be rotated, and thereby simultaneously, through the right and left hand screw-threads thereon, draw the top and bottom frames toward the double floor-frame, compressing the filtering material in the two strata, and so retarding the flow of the liquid through the filtering material. A reverse movement of the spindle-operating lever will simultaneously expand the strata of filtering material, and thereby increase the flow.

In Fig. 3 one compartment B represents the strata expanded and the other shows them compressed.

In assembling the several frames and plates suitable washer-rings may be inserted between them and the double floor-frame may be further secured in place by one or more set-screws i^3 , engaged with its periphery and the casing. The top and bottom plates are conveniently prevented from rotating by means of forked lugs e^2 and h' , extending, respectively, from the partition b and cover C , straddling the ribs e and h . The space between the perforated plates $K K'$ upon the opposite faces of the double floor-frame forms

the outlet-chamber common to the two filtering-strata and communicates with the delivery-pipe b^5 through the wall of the casing. A vent-pipe M extends along the periphery of the compartment and communicates with the spaces in proximity to the cover and partition b through ports m . A vent and drain cock m' , fixed to the cover C , serves to let off gases from the pipe M and said spaces when operating and for admitting air to within when blowing off or draining the compartment from the cock m' below. The cap g^3 upon the outside of the cover C forms an air-chamber, which communicates with the space beneath the cover by one or more channels g^4 , and a vent-cock g^5 communicates with the interior of the cap g^3 through the shank g of the spindle-operating lever.

To lift the covers for gaining access to the interiors of the compartments $B B'$, I provide a lever N , preferably bifurcated at one end, the branches n being adapted to enter sockets n' , formed in raised portions or a raised portion of the cover and removably secured therein by suitable keys n^2 . I also provide a catch n^3 for engaging the operating-arm of the lever and holding it in position to lock the cover open, as shown in dotted lines, Fig. 3.

The stand-pipes O and P , through which the liquid to be filtered is conducted to and led from the channels in the trunnions, are bolted and jam-nutted to the ends of the trunnions by means of bolts o and p , which pass through the pipes and screw into the rim of the fixed partition b . The joints between the trunnions and the stand-pipes are so packed as to admit of the rotation of the filtering-vessel relatively to the stand-pipes without causing a leakage. Additional supports for the stand-pipes are provided by brackets o' and p' , fixed to the standards a and engaged with the pipes. After the filtering-strata have been adjusted, either in the presence of water admitted into the compartments through the cocks b^{12} and b^{13} or in the absence of such water-supply, and the water-flush has been passed through the strata, as is common in starting, the liquid to be filtered may be admitted from the stand-pipe O through the channel b^6 into either one or both of the compartments $B B'$ through the channels $b^4 b^5$ into the space in proximity to the partition b . From there it percolates through the stratum of filtering material nearest the partition b , and also extends upwardly through the hollow spindle into the space beneath the cover, and thence percolates through the outer stratum of filtering material. In both instances the filtered liquid escapes from the strata of filtering material into the chamber formed by the double floor-frame, and is led thence into the branches of the outlet-channel within the opposite trunnion and thence into the discharge stand-pipe P .

It is obvious that the liquid to be filtered might be conducted by a continuation of the channels b^4 and b^5 along the periphery of the

vessel from each cock $b^8 b^9$ to the space beneath the covers instead of through the hollow spindle, and that in such event the spindle might be made without a passage through it. The form shown is, however, considered the more desirable, as it utilizes the hollow form of spindle in delivering the liquid centrally and avoids the necessity of extending the thickened portion of the rim of the partition b .

By the above construction and arrangement of parts two inletting-surfaces of the diameter of the filtering-vessel are provided in each compartment for passing the liquid to the filtering material and a common chamber provided for the two outletting-surfaces, also of the diameter of the vessel. The two compartments being arranged to operate independently of each other, one may be kept in operation while the other is being packed. The rate of flow of the filtered liquid and its condition may be regulated with the greatest precision by the simultaneous compression or expansion of the strata of filtering material in either compartment, and the provisions for blowing off gas and testing are conveniently located and readily manipulated.

What I claim is—

1. The combination, with separate strata of filtering material and plates held in position to retain one side of each strata fixed, of movable plates engaged with the opposite sides of the strata and means for moving the movable plates simultaneously toward and away from the fixed plates, substantially as set forth.

2. The combination, with separate strata of filtering material having their outletting sides facing each other and spaced apart, of frames or plates at the inletting sides of the strata, right and left hand screws for controlling the said frames or plates, and means for simultaneously operating the screws to force the plates toward and away from each other, substantially as set forth.

3. The combination, with the filtering-vessel, with its central partition impervious to liquid, and its covers, of separate strata of filtering material in each compartment of the vessel, spaced apart and spaced from the covers, plates located upon opposite sides of the separate strata, means for moving the plates at the opposite sides of the different strata in each compartment toward each other, conduits for conducting the liquid to be filtered to the spaces adjacent to the partition and the covers, and means for discharging the filtered

liquid from the space between the strata, substantially as set forth.

4. The combination, with a filtering-vessel having separate strata of filtering material located therein and spaced apart, of movable frames or plates in proximity to the opposite sides of the separate strata, a hollow spindle extending centrally through the strata and having a right and left hand screw-thread in engagement with the movable frames, chambers for the entrance of the liquid to the filtering-strata at or upon opposite sides of the different strata, said chambers being in communication with each other through the hollow spindle, a chamber for receiving the filtered liquid intermediate of the strata, means for rotating the spindle, and suitable inlet and outlet conduits, substantially as set forth. 75

5. The combination, with the spindle and plates provided with openings adapted to closely fit the body of the spindle, of a follow plate or frame provided with a screw-threaded opening and a removable screw-threaded collar or sleeve adapted to slide onto the end of the spindle into engagement with the screw-threaded opening in the follow plate or frame, and means for securing the said collar or sleeve to the spindle, substantially as set forth. 85

6. The combination, with the chambers for the entering liquid at the opposite ends of the compartments, of fixed conduits extending along the outside walls of the compartments and communicating with said chambers, and blow-off or vent cocks fixed to the covers and communicating with the said chambers, and hence with the conduits, substantially as set forth.

7. The combination, with the filtering-vessel, its conduits for the entrance of liquid thereto, and the water-inlet cocks in connection with said entrance-conduits, of the outlet-conduits, the stop-cocks connected therewith, and the auxiliary water-outlet cocks connected with the said stop-cocks in the outlet-conduits, substantially as set forth. 95

8. In combination with the fixed central partition, the hinged covers and the movable frames located in proximity to the partition and covers, the said partition and covers being provided with lugs which project toward the frames in position to engage their ribs and prevent them from rotating, substantially as set forth. 105
